UNITED STATES PATENT OFFICE.

BERNICE J. NOYES, OF BOSTON, MASSACHUSETTS, ASSIGNOR TO GEORGE W. GREGORY, OF SAME PLACE.

ELECTRIC SIGNALING APPARATUS.

SPECIFICATION forming part of Letters Patent No. 534,908, dated February 26, 1895.

Application filed July 5, 1892. Serial No. 439,000. (No model.)

To all whom it may concern:

Be it known that I, BERNICE J. NOYES, of Boston, county of Suffolk, State of Massachusetts, have invented an Improvement in Electric Signaling Apparatus, of which the following description, in connection with the accompanying drawings, is a specification, like letters on the drawings representing like parts.

In United States Patent No. 359,687, granted to me March 22, 1887, a police and fire alarm telegraph apparatus is shown comprising a receiving apparatus at a central station and signal transmitters located at sub stations and connected in circuit with the receiving apparatus at the central station, said signal transmitters being constructed and arranged to transmit two different classes of signals, as patrol or post signals and special signals, the latter class including such calls as wagon, telephone, and the like, and the receiving apparatus at the central station comprising a register adapted to record the signals received in code characters on a strip, and a bell or other equivalent indicating device or alarm mechanism, adapted to respond on the reception of the special calls, but to remain silent on the reception of the patrol or post signals. This patent besides generically claiming the above, also contains certain specific means by which the desired result is accomplished.

This invention has for its object to provide other novel means by which the results above specified can be carried out.

In accordance with this invention the bell or other alarm or indicating device which is to respond to certain signals and not to other signals, is an electrically controlled mechanically actuated device.

One part of this invention therefore consists in the combination with signal transmitters at the sub stations adapted to transmit two different classes of messages, over an electric circuit, and a message receiving instrument at the main station responsive to the changes in said circuit, of a special indicating device also located at the main station, and provided with a movable member actuated by a toothed wheel, and an electro-magnet to control the operative engagement of the said movable member and toothed

wheel, as will be described; also, in the combination with signal transmitters at sub stations adapted to transmit two different classes of messages over an electric circuit, and a message receiving instrument at the main station controlled by said circuit, of a special indicating device at the main station, provided with a movable member, a toothed wheel connected with and rotated by said receiving instrument to actuate said movable member of the indicating device, and an electro-magnet to control the operative engagement of said toothed wheel and movable member, as will be described.

Other features of this invention will be hereinafter described and pointed out in the claims.

Figure 1, represents in top or plan view partially broken away, a message receiving instrument, and a special indicating device, the mechanical actuator of which is operatively connected with a shaft of said instrument; Fig. 2, a side elevation of the apparatus shown in Fig. 1; Fig. 3, a plan view of a modified form of special indicating device, and Fig. 4, a diagram showing the essential circuits to illustrate my invention.

In connection with this invention any well known or suitable message receiving instrument or register may be employed, and such register may be either a single or multiple pen register although the latter form is preferable, as the signals from several circuits may be received and recorded upon the same strip of paper, and but one train employed. I have however in the present instance illustrated my invention in connection with a multiple pen receiver, substantially like that shown and described in United States Letters Patent No. 426,554, like letters representing like parts, said instrument being arranged to receive the signals from four separate circuits, and comprising a normally wound train, for moving forward the strip of paper upon which the message is recorded, an electro-magnet M, for releasing said train, four pen magnets as e⁴, and pens operated by them which press the paper against the marking wheels which are inked by suitable inking devices provided for the purpose. The pen magnets are included in local circuits, controlled by the relays K,

which are included in the separate signaling circuits.

The signal boxes or sub stations, are arranged in or included in the several signaling circuits at desired points, they each containing multiple signal transmitters, adapted to transmit two different classes of signals or messages, viz:—special signals which require immediate attention, and patrol signals which do not require immediate attention. Such signal boxes are herein represented at S, as included in the signaling circuits w, w', which circuits are normally closed, and hence the armatures of the relays in said circuits are normally attracted.

A creeper, such as shown in United States Patent No. 426,554, hereinbefore referred to, is provided, which operates on the occurrence of a change in the condition of the signaling circuit of long duration, the said creeper consisting of a sector m provided with a serrated edge loosely pivoted to an arm m' fixed to the shaft n', and a toothed or serrated wheel m² fixed to a shaft j², upon the periphery of which wheel the sector bears, all as in said patent. When the parts are at rest, as shown in Fig. 4, the sector m drops by gravity out of engagement with the wheel m², but just as soon as the magnet M is energized, the said sector is thrown into engagement with the wheel m², and by friction the said sector is raised or turned upwardly on its pivot. The arm carrying the sector being fixed to the shaft n' will be vibrated in response to the impulses and hence will retain the sector in engagement with the wheel m² much longer on impulses of long duration than otherwise. A pin projects from the sector, upon which rests the outer or free end of a contact pen m³ insulated from the contact pen m⁴. As the sector is lifted, the contact pen m³ is raised, and upon the occurrence of an impulse of long duration, said pin is raised sufficiently to make contact with the pen m⁴, and thereby close the local circuit t containing the local battery t' and electro-magnet t².

The patrol signals are composed of a series of short breaks or changes in the condition of the circuit, and the special signals are composed of a long break followed by a series of short breaks, and on the reception of a patrol signal the armature of one of the relays vibrates, closing the local circuit containing one of the pen magnets e⁴, and the releasing magnet M, thereby releasing the normally wound train and recording the signal or message upon the strip, and upon the reception of a special signal the same operation of the parts takes place, but in addition thereto the armature of the relay K is held retracted upon the occurrence of the long break, and the armature of the releasing magnet M correspondingly held attracted long enough for the creeper to operate and close the local circuit, and thereby attract the armature of the electro-magnet t².

The special indicating instrument herein

shown and which forms the subject matter of this invention, comprises a bell or gong R, supported on a suitable frame r, a striking lever r', which constitutes the movable member of the device, and an actuator, by means of which movement is mechanically imparted to said striking lever. The striking lever r', pivoted at r², is made in two parts, that is, its rear end r³, which engages the actuator, is separated from, but jointed to the main lever, and said rear end piece or arm r³, is connected with or supports the armature t³, of the electro-magnet t².

The actuator as herein represented consists of a toothed wheel u, secured to one of the shafts or arbors of the normally wound train of the message recording apparatus, as the shaft c⁸, for instance, said shaft being suitably extended that the toothed wheel may be secured thereto in proper position with relation to the jointed or two part striking lever to be engaged by said lever, and during such engagement as the toothed wheel revolves the striking lever is actuated to strike the gong.

Upon the reception of a special signal, as the creeper responds to the prolonged change in the circuit, as before stated, the armature t³, is attracted, moving the jointed end piece or arm r³, into engagement with the revolving actuator u, but such engagement is effected only on the occurrence of such prolonged change in the condition of the circuit. A spring r^x is connected to the striking lever which acts thereon in opposition to the movement given to it by the actuator. Thus it will be seen that upon the reception of the special signals the bell will respond, but upon the reception of the patrol signals the bell will remain silent.

I do not however desire to limit my invention to the particular means herein shown for moving the striking lever r, or part thereof into and out of engagement with the toothed wheel or actuator, as it is obvious that in lieu of a prolonged change in the condition of the circuit, any other differentiating impulse may be employed to affect the electro-magnet t², on the reception of the special signals and not on the reception of the patrol signals.

In Fig. 3, the toothed wheel or actuator is arranged to be moved longitudinally on the shaft c⁸, by means of the armature of the electro-magnet t², and the striking lever is represented as composed of a single piece, or pieces rigidly connected together, and in this instance it will be seen that the same result is produced as above described, the actuator being moved into engagement with the lever instead of the lever into engagement with the actuator.

I claim—

1. The combination with a message recording instrument located at a main station, one or more signal transmitters located at sub-stations adapted to transmit two different classes of messages, and an electric signaling

circuit connecting the same, of a bell or other indicating device also located at said main station, having a movable or striking member, a toothed wheel to actuate said movable or striking member, a normally wound train to move said actuator, and an electro-magnet controlled by the circuit which controls the operative connection between the said toothed wheel and said movable or striking member 10 of the bell or indicating device, substantially as described.

2. The combination with a message recording instrument located at a main station, one or more signal transmitters located at sub-stations adapted to transmit two different classes of messages, and an electric signaling circuit connecting the same, of a bell, a two part striking lever therefor, and an actuator for the striking member, and an electro-magnet controlled by the circuit, which moves one part of the striking lever into engagement with said actuator, substantially as described.

3. The combination with a message recording instrument located at a main station, one or more signal transmitters located at sub-stations adapted to transmit two different classes of messages, and an electric signaling circuit connecting the same, of a special indicating device also located at the main station, a mechanical actuator therefor connected with and moved by the normally wound train of the recording instrument whenever the said train operates, and an electro-magnet controlled by the circuit which controls the operative connection between the said actuator and said special indicating device, substantially as described.

4. The combination with two or more electric signaling circuits, each containing one or more signal transmitters adapted to transmit two different classes of messages and a message recording instrument having two or more pen magnets controlled by said circuits, of a special indicating device also located at the main station, a mechanical actuator therefor,

driven by the normally wound train of said recording instrument, and an electro-magnet controlled by the circuit which controls the operative connection between said actuator and special indicating device, substantially 50 as described.

5. The combination with a message recording instrument located at a main station, one or more signal transmitters located at sub-stations adapted to transmit two different 55 classes of messages, one of which includes a differentiating impulse, and an electric signaling circuit connecting the same, of a bell or other indicating device also located at said main station having a striking lever, a toothed wheel to actuate said striking lever driven by a normally wound train, an electro-magnet affected by said differentiating impulse, which controls the operative connection between said toothed wheel and striking lever, substantially 60 as described.

6. The combination with a message recording instrument located at a main station, and one or more signal transmitters located at sub-stations adapted to transmit two different 70 classes of signals, one of which includes a prolonged change in the condition of the circuit, and an electric signaling circuit connecting them, of a bell or other indicating device also located at said main station having a striking lever, a toothed wheel to actuate it driven by a normally wound train, and an electro-magnet affected by said prolonged change in the condition of the circuit which controls the operative connection between said toothed 75 wheel and striking lever, substantially as described.

In testimony whereof I have signed my name to this specification in the presence of two subscribing witnesses.
